(57) **CLAIM**

The ornamental design for a motorcycle foot peg, as shown and described.

DESCRIPTION

FIG. 1 is a front perspective view of a motorcycle foot peg intended as the left side embodiment for the left side of a motorcycle;

FIG. 2 is a front elevation view thereof;

FIG. 3 is a rear elevation view thereof;

FIG. 4 is a right side elevation thereof;

FIG. 5 is a left side elevation view thereof;

FIG. 6 is a top plan view thereof;

FIG. 7 is a bottom plan view thereof; and

FIG. 8 is a bottom perspective view thereof.

FIG. 9 is a front perspective view of a motorcycle foot peg intended as the right side embodiment for the right side of a motorcycle;

FIG. 10 is a front elevation view thereof;

FIG. 11 is a rear elevation view thereof;

FIG. 12 is a right side elevation thereof;

FIG. 13 is a left side elevation view thereof;

FIG. 14 is a top plan view thereof;

FIG. 15 is a bottom plan view thereof; and,

FIG. 16 is a bottom perspective view thereof.

The broken lines in the drawings illustrate portions of the motorcycle foot peg that form no part of the claimed design.
